(57) **CLAIM**

The ornamental design for a positionable tool light, as shown and described.

DESCRIPTION

FIG. 1 is a perspective view of one embodiment of the positionable tool light.

FIG. 2 is a side perspective view of the positionable tool light.

FIG. 3 is a front perspective view of the positionable tool light.

FIG. 4 is a rear perspective view of the positionable tool light.

FIG. 5 is a top plan view of the positionable tool light; and, FIG. 6 is a bottom plan view of the positionable tool light.

(Continued)

The broken lines in FIG. 6 depict unclaimed structure which is not intended to form a part of the claimed design.

1 Claim, 3 Drawing Sheets
